CORSET AND COMBINATION GARMENT

Blanche F. Hall, Kansas City, Mo.

Application January 15, 1944, Serial No. 518,442

6 Claims. (Cl. 2—43)

In general, this invention relates to foundation garments and to include corsets, girdles, etc.

More specifically, the invention relates to a new and improved corset and combination garment. This garment comprises a tubular body portion and a bifurcated lower portion. In other words, the garment consists of a portion that encircles the body, or a portion of the body, of the wearer, and the lower portion thereof being bifurcated, constitutes separate leg openings which surround the upper portions of the thighs of the wearer. In addition, this new garment includes a novel crotch structure and arrangement which with the lower portion of the outsides of the girdle constitutes the remainder of the enclosures providing the leg openings.

The corset in effect is a foundation garment embodying therewith a pantie front and crotch and a corset back.

Heretofore, girdles, corsets, and other foundation garments have been constructed so as to perform a function only of supporting the mid section including the stomach and abdomen and projecting downwardly over the extreme upper outer portions of the thighs of the wearer, and this type of corset has been tubular in construction and does not provide for an undergarment serving as a corset or girdle, as the case may be, and what might be called panties, in a unitary structure.

It is an object of my invention to provide a novel corset embodying therewith as a permanent unitary part thereof, a lower bifurcated portion including a novel crotch structure and arrangement and a portion of the latter serving with a portion of the lower outside portion of the corset to provide leg openings. This new corset is one that will require little or no manipulation by the wearer in permitting the functions of nature to perform in a most natural way. In other words, with the present type of corsets, foundation garments, or girdles the pressure on the stomach and abdomen of the wearer, even pulled up, as usual, still exerts sufficient force as to hamper the function of nature in a natural and uninhibited manner.

The invention will be more clearly understood by referring to the accompanying drawings, wherein:

Figure 1 is a perspective view of the garment as viewed from the front thereof;

Figure 2 is a perspective view of the garment showing the rear thereof closed;

Figure 3 is a vertical sectional view on the lines 3—3 of Figure 1;

Figure 4 is a vertical sectional view on the lines 4—4 of Figure 2;

Figure 5 is a vertical sectional view of Figure 1;

Figure 6 is a perspective view of the novel crotch structure before being applied to the girdle;

Figure 7 is a cross sectional view on the lines 7—7 of Figure 1; and

Figure 8 is a rear perspective view of a modification showing the invention having its rear panel opened and the crotch structure in open position.

Referring more specifically to the drawings, it will be seen that the corset comprises an upper tubular portion or body indicated generally at A and a lower bifurcated portion indicated generally at B. The novel crotch structure is indicated generally at C.

The body portion of the corset A and the lower 20 outside portions of the bifurcated leg structures are made of suitable non-stretchable, preferably porous, and in some instances, lined textile material. Lastex or other elastic diametrically disposed inserts indicated at D are provided, and 25 they extend substantially from the top to the bottom of the garment at the opposite sides thereof. A suitable slide fastener indicated at S is provided adjacent the left side of the corset and it extends from the upper edge thereof down to 30 a point substantially opposite the bifurcated lower portion of the garment. This slide fastener when opened, permits the garment to be readily applied and removed from the wearer. Another slide fastener in the rear of the garment indicated at T is provided for a purpose later described herein.

The crotch structure C consists of two similarly shaped flaps 8 and 10 of suitable material, preferably textile material, which when in closed position are in overlapped contacting arrangement such as clearly shown in Figure 6. The overlapping flaps continue from the line of stitching 11 and form the rear or seat portion 12 of the panties proper. Integral with the seat portion, 40 the lower extremities 13 constitute substantially one-half of the enclosure for the legs of the wearer. The ends or panel 14 join in front as shown in Figure 1. A plurality of pleats 15 are formed in the extension of the seat portion, and these pleats gather in the material at the edges, later to be described, and are sewed to the inside of the garment and provide a fullness in the seat portion of the panties. The upper free end of each of the aforesaid overlapped flaps has attached thereto an elastic tape 16.

By referring to Figures 1 and 2, particularly, it will be seen that the combined crotch and leg portions which constitute the panties as designated in Figure 6 is attached by means of sewing to the interior of the corset. Each of the edges 17 of the pantie is sewed to the interior of the garment at 18 and it will be noted that this line of stitches is in overlapped relationship with the rear part of the oppositely disposed elastic inserts D. Each of the front edges 19 constituting a portion of each of the leg openings, is stitched to the lower portion of the corset as at 20 and this line of stitching, as will be clearly seen in Figure 1, extends directly up to the crotch portion of the garment. It is understood that the overlapped smaller end portions of the crotch formation is stitched to the corset proper as indicated at 22. By referring particularly to Figures 1 and 3, it will be noted that each of the elastic straps or tabs 16 have their respective ends stitched to the interior of the garment as at 21 to permanently anchor the free ends of the overlapping flaps within the garment. By referring particularly to Figure 3 it will be noted that each of the elastic tabs or straps extend over each of the elastic inserts D in the garment. This design 20 garment will require different anchorage distances.

With the combined crotch and leg portions as indicated in Figure 6 permanently associated with the corset as shown in Figures 1 and 2, it is clear that the corset comprises an upper tubular portion and a lower bifurcated portion, the latter being formed by a portion of the corset proper and the portions 13 of the combined crotch and 30 leg portion insert.

The corset proper consists of two or more front panels 23, 24, 25 and 26, the two oppositely disposed elastic inserts D and and three rear panels 27, 28 and 29, each of which is stitched at 30 to the other to comprise the tubular garment as a whole. By referring particularly to Figures 2 and 8, it will be noted that the three said rear panels extend downwardly below and over the crotch structure portion of the garment and over a portion of the separate legs of the garment, thereby constituting a corset back. The main rear panel 28 is provided at its lower portion with a slide fastener U and it will be noted that this slide fastener opens upwardly to a point substantially mid-way of the garment and thereby permits the aforesaid overlapping crotch flaps to be separated when the occasion demands. The elastic tabs or straps 16 will permit a relatively wide opening of the said flaps when the occasion demands and will also serve to automatically, so to speak, withdraw these flaps into their original overlapped desired position. Figure 8 represents a good illustration of the manner in which the flaps can be separated or opened when the slide fastener of the main rear panel 28 has been drawn upwardly, and also shows a slight modification of the invention, as embodied with a full foundation garment or corset.

In Figure 8, the structural characteristics of my invention are precisely the same as described hereinbefore with regard to Figures 1 to 7 but including the breast supporting portion H with shoulder straps h and garter straps J.

It is to be noted that the slide fastener S is covered on the interior of the garment by means of a flap 31 sewed at one side edge 32 to the interior of the garment. This flap 31 serves to prevent contact of the slide fastener with the body of the wearer.

The aforesaid panels constituting this corset may, of course, each be lined with a suitable fabric as is now customary. In other words, the main panel portions of the garment may constitute two thicknesses of material.

From the foregoing, it is believed quite clear that this combined corset and pantie with its novel crotch structure constitutes a garment having all of the inherent structural characteristics permitting proper support of the parts of the wearer and also permitting the wearer to meet the demands of nature without having to pull the garment up or down or remove the same. The structural characteristics of this garment are such that when the wearer thereof is in the act of complying with the demands of nature, the garment will not exert any unnatural or any undesirable pressure on the parts of the anatomy and consequently therefore is conducive to one's good health and convenience and practicability in the use of the same.

Various modifications of the invention may be resorted to without departing from the spirit of the invention within the scope of the claims appended hereto.

What is claimed is:

1. In a garment of the character described, a tubular upper body portion and an integral lower bifurcated portion each forming a part of a leg opening, a combined crotch, seat, and partial leg-forming construction sewed to the garment and including normally overlapped flaps forming the seat and integral continuations thereof each sewed to and providing with the said lower bifurcated portion of the garment separate complete leg openings for the wearer, said flaps being capable of being opened when desired.

2. A combined corset and pantie having a pantie front and crotch and a corset back consisting of a tubular upper body and an integral lower bifurcated pantie which forms a part of leg openings, a crotch structure sewed to the corset, the front of said corset extending down to and joined with the crotch thereat and constituting the said pantie front and the back of said corset extending downwardly past the said crotch and constituting the corset back, the said crotch structure including a combined crotch, seat, and partial leg-forming opening construction and consisting of normally overlapped flaps each having opposed side edge portions attached to the interior of the corset and also having opposed free edge portions, and integral continuations thereof forming with the said bifurcated portion of the corset separate leg openings for the wearer, and fastening means for opening and closing that said downwardly extending portion of the back of the corset whereby when same is opened the said flaps may be separated.

3. A garment as described in and by claim 2 wherein each of said flaps has its opposed side edge extended portion sewed to the interior of the garment at oppositely disposed points therein, and the free edge portions of each of said flaps has attached at its upper ends an elastic tape, the free ends of which are also secured to the interior of the garment at the oppositely disposed points therein whereby when said flaps are opened the elasticity of said tapes will permit a wide opening thereof and also serve to restore said flaps to their normal overlapped relationship.

4. In a garment of the character described, a tubular upper body portion and a lower bifurcated portion, a normally closed crotch structure combined with said garment so as to effect a lower pantie front, the rear of the body portion extending over said crotch structure at the rear of the garment and constituting a corset back, and means for opening that portion of the body of the garment extending over the said crotch structure so that the said crotch structure may be opened when necessary.

5. In a garment of the class described, a tubular upper body portion and a lower bifurcated portion, a normally closed crotch structure permanently secured to said garment so as to effect an integral lower pantie front, and the rear of the body portion of the garment extending downwardly and over said crotch structure at the rear thereof and constituting a corset back and

slidable means for opening and closing that said portion of the body of the garment which extends over the said crotch structure at the rear of the garment whereby when the said closure means is open the said crotch structure may be opened.

10 5. In a garment of the character described, a tubular upper body portion and lower bifurcated leg portions, a normally closed crotch structure secured to the garment to effect an integral pantie front with said leg portions, the rear of the body portion extending downwardly over the crotch structure and over a part of the leg portions, and a slidable fastener for opening the 15 rear downwardly extending portion up to a point substantially mid-way of the lower rear portion of the garment.

BLANCHE F. HALL.
